CLAIM

The ornamental design for a closure for a container for chemical and radioactive waste, as shown and described.

DESCRIPTION

FIG. 1 is a side elevational view of a closure for a container for chemical and radioactive waste showing my new design;

FIG. 2 is a top plan view;

FIG. 3 is a fragmentary cross-sectional view taken on line 3—3 of FIG. 2 with a portion of a container being shown in broken lines to illustrate environmental use only; and

FIG. 4 is a bottom plan view.

FIG. 1.

FIG. 2.

FIG. 3.

FIG. 4.
